UNITED STATES PATENT OFFICE.

CUMMINGS CHERRY, OF PITTSBURG, PENNSYLVANIA.

IMPROVEMENT IN APPARATUS FOR PURIFYING OIL OBTAINED FROM MINERAL COAL.

Specification forming part of Letters Patent No. 15,642, dated September 2, 1856.

To all whom it may concern:

Be it known that I, CUMMINGS CHERRY, of Pittsburg, in the county of Allegheny and State of Pennsylvania, have invented a new and useful Improvement in Apparatus for Refining and Purifying Oil Extracted from Coal or other Bituminous Minerals; and I do hereby declare the following to be a full, clear, and exact description thereof, reference being had to the annexed drawings, forming part of this specification, in which—

Figure 1 is a ground plan of my apparatus. Fig. 2 is an elevation of the apparatus shown in Fig. 1. Fig. 3 is a representation of the oil-tank and gasometer. Fig. 4 is a representation or front view of the horizontal retorts. Fig. 5 is a longitudinal sectional view of one of the horizontal retorts. Fig. 6 is a sectional view of the second condenser and stirring cistern. Fig. 7 is a representation of the blade of the stirrer. Fig. 8 is a sectional view of the second stirring-cistern. Fig. 9 is a transverse sectional representation of the steam-boiler and oil-boiler and their furnace. Fig. 10 is a longitudinal sectional view of the oil-boiler.

My invention consists in certain new and improved apparatus for purifying the crude oil obtained from bituminous coal specially adapted to that purpose, and by means of which the oil is fitted for the purposes of illumination or other objects to which it may be applicable. The crude oil which I treat is procured by distillation from bituminous or gas coal or other bituminous minerals by a process invented by myself, but not necessary here to explain. When first produced this oil is extremely offensive, and to render it fit for use for burning in lamps or for other purposes to which the fixed oils of commerce are applicable it is necessary to purify it by removing the impurities—such as creosote, tar, ammoniacal water, and other crude substances—which impart a high color and offensive odor to the oil in its crude state. In order to accomplish this object I subject the crude oil to a certain process of purification, which forms the subject of a distinct application for a patent. I shall therefore in this specification only describe this process so far as is necessary to explain the objects and uses of the apparatus I describe.

The process of purification may be either

carried on distinct from the manufacture of the crude oil or immediately in connection with it. I shall therefore describe my purifying apparatus as connected with the manufacture, suggesting the obvious alterations necessary, if this is not the case. The vapor of the crude oil, as it passes from the manufacturing retorts, in which it is extracted from the coal, traverses the worm *o* in the prime condenser *F*, (see Fig. 3,) and is there condensed, whence it passes as crude oil through the pipe *G* into the oil tank or receiver *H*. If the purifying process is carried on distinct from the manufacture of the oil, the crude oil is put in the first place into the tank or receiver *H*, Fig. 3, the subsequent process in either case being the same, excepting so far as relates to precautions taken to dispose of any permanent gas which may pass into the oil-tank *H* from the manufacturing-retort, which would not exist if the manufacturing of the crude oil is not connected with the purifying process. From the prime condenser *F*, Fig. 3, the crude oil, together with any gas which may have been generated in the manufacture of the oil, passes through the pipe *G* into the oil-tank *H*, (see Fig. 9,) in which and the adjoining tank *H'* the crude oil is allowed to stand for a time in case it has just been manufactured—say from three days to a week—in order to settle and become more fully condensed. A pump, *p*, is inserted through the top of the tank *H*, and extends down to the bottom of the cistern to pump the crude oil out into the gutter or conduit *q*, by which it is conducted into the horizontal retorts. The tanks *H* and *H'* are connected by a pipe, *p'*, leading from the bottom of *H'* to near the bottom of *H*, so that when there is an excess of oil in *H* it may be drawn off into *H'*, where it is allowed to settle until needed for use. The tank *H'* serves as a gas-meter in which is collected the gas not condensed in the prime condenser *F*. The covering *r* of the tank *H'* being set in a water-joint, (see Fig. 3,) as is usual with gas-holders, is hung on a chain over a pulley, and balanced by weights, so as to rise or fall as the gas enters or passes out. A gas-pipe, *s*, leads from the top of the oil-tank *H* to the bottom of the tank or meter *H'*, and, rising up through the latter above the level of the oil, discharges the gas from the tank *H* to the meter *H'*, whence the gas is taken and

purified in the ordinary manner, and may be used for illuminating or heating purposes. The crude oil, being pumped out of the tank H into the conduit q, runs down to the horizontal retorts I I. (See Figs. 1, 4, and 5.) These retorts are made of cast-iron, two inches thick, and of cylindrical shape. They are set in an oven built of fire-brick, and are supported inside the oven by an arch of fire-brick constructed with interstices between the bricks to admit the passage of the fire and heat through the arch to the retort. (See Figs. 4 and 5.) The under surface of the horizontal retorts I I is surrounded with a casing of fire-brick, t, for the reason that if the fire were allowed to act immediately on the bottom of these horizontal retorts, they would soon be burned out, and because when once heated they are thus kept at a more uniform degree of heat and are less susceptible to change of temperature. The crude oil, passing along the conduit q, enters the rear end of the horizontal retorts through the pipe w, which is furnished with a stop-cock, x¹, to close the pipe when oil is not being admitted. From the forward end of the retort rises a perpendicular pipe, v, furnished with two copper heads, J and L, one above the other, and each surrounded with a jacket, K and M, containing cold water. From each of these heads J and L passes a pipe—N from the lower head, J, and O from the upper head, L—(see Fig. 5,) both of which pipes open into the receiver P, which is placed at the rear end of the retorts. This receiver P is tubular, and is placed horizontally over the series of horizontal retorts I I, and is connected with each retort by a short pipe, w. Each of the pipes N, O, and w is furnished with a stop-cock x, x¹, and x².

From the bottom of the receiver P, immediately above its connection with the pipe w, is a horizontal pipe, y, which opens into the rectifying-chamber Q; which is an iron chest furnished with trays z z, on which are placed layers of fresh unslaked lime. In front of each horizontal retort I I is placed a thermometer (see a' a', Fig. 4) the bulb of which communicates with a small tube, b', leading from the interior of the retort, by means of which, by turning a small stop-cock in the tube b', and allowing the contents of the retort to come in contact with the bulb of the thermometer, the exact degree of heat in the retorts may be ascertained. The crude oil from the tanks H H' having been run into the horizontal retorts, as already stated, there is added to it in the retorts an alkaline solution of caustic potash or caustic lime, after which the retorts are closed, and the three stop-cocks—namely, x in the pipe N, x² in the pipe w, and x³ in the pipe y—being closed, and the stop-cock x¹ in the pipe O being opened, the process of distillation is commenced. The heat is raised to about 350° Fahrenheit, and the mixture of oil and alkaline solution is kept boiling from six to twelve hours. The only exit for the vapor being through the up-

right pipe v, and the heads J and L being kept surrounded by cold water in the jackets K and M, the vapor is continually condensed and running back again down the pipe v into the retort, and thus is distilled over and over again. Whatever vapor is not condensed in the heads J and L passes down the pipe O into the receiver P, where it condenses, and whenever it is desired it may be let into the retort again through the pipe w by turning the stop-cock x². After this process has been continued from six to twelve hours I reduce the heat so as to stop the ebullition of the contents of the retort, and the oil will then rise to the top of the alkaline solution, which latter is drawn off from below by the cocks c' c', leaving the oil only in the retorts. The water is also drawn off from the jackets K M around the heads J L by the cocks c' c', it being no longer desired to condense the oil in the heads, and any oil which may have collected in the receiver P is run back into the retorts by turning the stop-cock x² in the pipe w. The cock x¹ in the pipe O being then shut, and, the cocks x and x³ in the pipes N and y being opened, (the cock x² in the pipe w being still closed,) the heat is again raised and the vapor of the oil passing through pipes v and N, and through the receiver P and pipe y, enters the rectifying-chamber Q, where it passes over the line laid on the trays z z, and is thus purified from acids and other impurities. The oleaginous vapor thence passes from the rectifying-chamber Q, through a pipe, d', into a second condenser, R, where it traverses the refrigeratory worm e', which is immersed in water at the temperature of about 50° Fahrenheit. Here, being again condensed into oil, it runs through the pipe f' into the cistern S, which is open at the top and lined with lead. To the oil in this cistern is added from time to time dilute nitric or muriatic acid about half a pound to the gallon of oil. This must be well mixed with the oil, and to effect this a paddle, made of wood and covered with lead, of the shape shown in Fig. 7, and marked L in Fig. 6, is inserted in the cistern S, to which an oscillating motion is communicated by a crank, g', and lever h'. (See Fig. 6.) This paddle, passing rapidly backward and forward through the oil and acid, intermingles them effectually. After this process is continued for about four hours the oscillations of the paddle cease, and the oil remains in the cistern S until separated from the thickened acid, when it is drawn off by the pipe i' into a close circular cistern, T, which is also lined with lead. In this cistern T is a perforated paddle, k', of the shape shown in Fig. 8, which revolves on its axis, being geared to the main shaft by the wheels l' m', in order to mix thoroughly with the oil a weak solution of caustic lime, which is added to it in the cistern. After mixing for three hours there is added to the oil and lime about a quarter of a pound of nitric or muriatic acid to every gallon of oil, and the revolutions of the paddle k' are continued for three hours longer.

It is then allowed to settle until the oil separates itself from the lime and acid, when the oil is drawn off into a suitable receptacle and returned to the horizontal retorts I I, where it is again distilled, and, passing through the rectifying-chamber Q and the refrigeratory worm e in the condenser R, it is pumped into the boiler U, (where there is added to it about half a pound of caustic potash to every gallon of oil,) and is there exposed to the direct action of steam. This I effect as follows: Two cylindrical iron boilers, U and V, are placed side by side over a furnace. (See Fig. 9.) The boiler V is a boiler such as is ordinarily used for the generation of steam from water, and the boiler U is like it, excepting that a long steam-pipe, n', extends horizontally from one end to the other of the boiler U and within a short distance of the bottom. This pipe is closed at both ends, but is perforated throughout its length with small holes, to allow of the escape from it of the steam from the boiler V. A pipe, W, from the top of the steam-boiler V, connects the steam-pipe n' with the steam-chamber of the boiler V, passing down through the oil-boiler U, and uniting with the horizontal pipe n' at right angles thereto. A stop-cock, o', or valve regulates the admission of steam from the steam-boiler V into the oil-boiler U, and stop-cocks q' q' at the bottom of the oil-boiler U allow the water from the condensed steam to be drawn off when the boiling is terminated. The oil is kept boiling for twelve hours, during all which time the steam from the boiler V is admitted into the boiler U, and passes through the oil.

The foregoing is a description of all the apparatus necessary to be used for purifying the crude oil; but the process of purification does not stop here, but the apparatus already described is used for the subsequent parts of the process, which are briefly as follows: The oil is drawn off from the oil-boiler U into the lead-lined cistern S, where it is mixed by the

paddle L, Fig. 6, with a solution of caustic potash of the same strength and quantity as before, and is then drawn off or pumped out and returned to the horizontal retorts I I, Fig. 5, and again distilled and passed over the line in the rectifying-chamber Q, Fig. 5. It is then again steamed and boiled in the oil-boiler U, Fig. 9, after which it is mixed by the paddle L with nitric or muriatic acid in the cistern S, Fig. 6. After settling, the oil is drawn off from the acid and placed in a suitable vessel with fresh burnt lime, where it remains about a week at a temperature of 60° Fahrenheit, to allow all impurities to settle. The oil is then fit for use, being highly inflammable, extremely volatile, and very fluid. A greater degree of purity may be obtained by a further repetition of the distilling and steaming processes, and treatment with caustic lime, potash, and acids, as described, or by filtration through pulverized animal charcoal, &c.

Having thus described my improved apparatus for purifying crude oil obtained from bituminous coal and other bituminous minerals, I wish distinctly to be understood that I do not claim any of the individual parts of my apparatus *per se*; but

What I do claim as my invention, and desire to secure by Letters Patent, is—

The arrangement of the horizontal retorts I I, as combined with the copper heads J and L of the rectifying-chamber Q of the steam-conduits to the oil-boiler, and of the agitating apparatus, in the manner and for the purposes described.

In testimony whereof I have hereunto set my hand this 5th day of December, A. D. 1855..

C. CHERRY.
